UNITED STATES PATENT OFFICE.

BARNEY L. HUFF, OF JEAN, TEXAS.

MAIL-BAG CATCHER.

1,186,907.

Specification of Letters Patent. Patented June 13, 1916.

Application filed August 30, 1915. Serial No. 48,050.

To all whom it may concern:

Be it known that I, BARNEY L. HUFF, citizen of the United States, residing at Jean, in the county of Young and State of Texas, have invented certain new and useful Improvements in Mail-Bag Catchers, of which the following is a specification.

This invention relates to an improved mail bag catcher and the principal object of the invention is to so construct the device that the train device and track device may be provided with substantially the same construction and thus make it unnecessary to provide a device of a special construction for either the train or the track device, both devices being as stated before of substantially the same construction.

Another object of the invention is to provide improved means for engaging the mail bag to remove the same from the holding means.

Another object of the invention is to so mount this engaging means that it may be used for receiving a mail bag from a car traveling in one direction as well as in another.

Another object of the invention is to provide improved means for mounting the jaws which are part of the engaging means, the jaws being yieldably held in a closed position and releasably held in an open position by a trigger engaged by the caught sack.

Another object of the invention is to provide improved means for releasably holding the mail bag in a position for engagement by the engaging means.

This invention is illustrated in the accompanying drawings, wherein:

Figure 1 is a view in elevation showing the track device and train device in set position. Fig. 2 is a fragmentary view taken along the line 2-2 of Fig. 1.

From an inspection of Fig. 1 it will be readily seen that the train device and track device are substantially the same in construction each comprising a standard carrying bag supporting arms one of which is yieldably held in a normal position and also carrying an arm for supporting the engaging element which is pivotally mounted and comprises a pair of jaws yieldably held in a closed position and releasably held in an open position by a trigger engaged by the sack when caught. Therefore the parts of the train device and track device are inter-

changeable and thus the cost of manufacturing is reduced.

The standard 10 of the train device is formed from a length of piping which carries ears 11 through which the pins 12 of the bracket 13 pass thus pivotally mounting the standard 10 and permitting it to be swung from the position shown in Fig. 1 to an inoperative position. The sack holding arms 14 and 15 are carried by the standard 10, the arm 14 extending through the standard and thus being rigidly mounted and the arm 15 being pivotally mounted upon the pin 16 so that it will have vertical swinging movement. A spring 17 is provided with one end connected with the inner end of arm 15 and the opposite end connected with the eye 18 carried by the bar 19. This spring will therefore tend to normally hold the outer end of the arm 15 in a raised position and thus cause a frictional binding between the pin 20 of the arm 15 and the ring 21 of the mail bag indicated by dotted lines when the bag is put in place with its upper ring 21 engaging the pin 20 and its lower ring 22 engaging the pin 23 of the lower arm 14. The arm 14 is braced by the braces 24 and 25, the brace 24 leading to the bar 19 and the brace 25 leading to the arm 26 which carries the engaging element of the train device.

From an inspection of Fig. 2 it will be seen that the engaging element comprises the inner and outer jaws 27 and 28, the inner jaw being the stationary jaw and the outer jaw being the movable jaw. These two jaws carry plates or hinged ears 29 which are overlapped as shown in Figs. 1 and 2 and connected by the pivot bolts 30 which also serve as means for carrying the spring 31. This spring 31 has its coil placed about the bolt 30 between the hinge and has its lower arm 32 engaging the stationary jaw 17 and its upper arm 33 engaging the movable jaw so that the movable jaw will be normally held in a closed position. It is desired to have the jaws releasably held in an open position so that the mail bag can pass between the same and therefore the trigger 34 has been provided with its inner end hinged to the stationary jaw by means of the hinge 35 and its free end adapted to engage the outer end portion of the movable jaw as shown in Fig. 2. In order to permit this engaging device to be used for either up track or down track service it is

necessary to have the catching element pivotally mounted and therefore the stationary jaw has been provided with an enlargement or shoulder 36 which fits between the arm 37 of the block or bearing 38. This block fits against the end of the arm 26 and is pivotally connected therewith by means of the bolt 39 which passes through the arm 26 and is held in place by the nut 40 mounted upon its inner end. An abutment 41 is provided so that when a sack is caught the finger 42 will engage the abutment 41 and prevent the engaging element from rotating and thus giving the mail sack a chance to slip from between the jaws 27 and 28 before it has been firmly engaged.

The station or track device is very similar in construction to the train device and will now be described briefly, some reference being made to the detail description in connection with the train device since it is not thought necessary to repeat the detail description of the parts which are the same. The standard 43 carries the sack holding arms 44 and 45 which are similar to the arms 14 and 15, the arm 44 being stationary and the arm 45 being pivotally mounted upon the pin 46 and having vertical swinging movement in the slot 47 of the standard. This arm 45 is yieldably held in the normal position by the spring 48 so that rings 49 and 50 of the sack will be held in tight engagement with pins 51 and 52 of the holding arm, the spring being connected with the bar 53 which corresponds to the bar 19 and braced by the brace 54 leading to the arm 44. It should be noted that the arm 55 which corresponds to the arm 26 is provided with the brace 56 in addition to the brace 57 and that the brace 56 which extends diagonally serves the double purpose of bracing the outer end of the arm 55 and taking the place of the abutment 41. The engaging element of this station device is identical with the train device and comprises the inner stationary jaw 58 and outer movable jaw 59 which is pivotally connected with the stationary jaw and yieldably held in a closed position by the arm 60 of the spring and releasably held in an open position by the trigger 61 corresponding to the trigger 34. In this device the stationary jaw is rigidly mounted between the arms of the block 62 by means of the bolts 63 so that when the block turns upon the pivot bolt 64 which corresponds to the bolt 26 the engaging device will be rotated with it. Abutment fingers 65 similar to the abutment fingers 42 are provided and engage the diagonal brace 56 to limit the rotary motion of the engaging element. It is not necessary to have the standard 43 rotatably mounted in the manner that the standard 10 is, since this standard 43 is mounted adjacent the track or upon the station platform and does

not need to be swung out of the way when not in use.

When using this device the mail bags are suspended from the hooks of the arms carried by the standards 10 and 43 as shown by the dotted lines and the catching devices are turned so that the open ends of the jaws will face in the direction in which the train is moving. The jaws are held open by the triggers 34 and 61 and since the triggers are adjacent the outer ends of the jaws a mail bag cannot pass between the same without the triggers being sprung and permitting the springs to move the movable jaws 28 and 59 to a closed position to clamp the mail bags between the same and the stationary jaws. After the mail bag has been delivered and a mail bag caught the caught bag can be removed from between the jaws of the catching element of the train device and if the mail bag handling device is not to be used again until the return trip the same may be swung against the side of the car where it will be out of the way. If however a mail bag is to be delivered at a following station or a mail bag to be taken up the second bag will be put in place and the catching element set and the process repeated. After the caught sack has been removed from the station device and it is desired to remove a sack from a train upon the return trip the catching element will be turned to face the direction from which the train will approach and set to catch the sack from the train and a sack to be delivered to the train will be placed between the supporting arms 44 and 45.

I have therefore provided a mail sack catching and delivering apparatus which is so constructed that the various parts of the train device and station device will be interchangeable, thus making the cost of manufacture and instalment comparatively small. It will also be noted that I have provided a device in which the engaging element is very simple in construction but very effective in operation. It will also be noted that the engaging device is so constructed that it may be used for removing sacks from trains moving either up the track or down the track and that therefore this device can be used upon single track lines with very great facility. It should be further noted that this device is so constructed that the mail sack will be very securely held until removed from the holding arm and that when removed it will be very securely held until removed from between the jaws of the engaging device by the station master or mail clerk in the train car.

What is claimed is:—

1. In a sack handling device a supporting bar, a block pivotally connected with said bar and provided with spaced arms, means for limiting the rotary movement of

said block, a stationary jaw rigidly mounted between said arms, a movable jaw, hinged ears extending from said jaws, a pivot pin connecting said ears to pivotally mount said movable jaw with respect to said stationary jaw, a spring mounted upon said pin and provided with arms engaging said movable and stationary jaws to normally hold said movable jaw in a closed position, and a trigger pivotally connected with one of said jaws and having its free end engaging the other of said jaws to releasably hold said jaws in an open position.

2. In a sack holding device a supporting bar, a block connected with said bar, a stationary jaw rigidly connected with said block, a movable jaw, hinged ears extend-

ing from said jaws, a pivot pin connecting said ears to pivotally mount said movable jaw with respect to said stationary jaw, a spring mounted on said pin and provided with arms engaging said movable and stationary jaws to normally hold the movable jaw in a closed position, and a trigger pivotally connected with one of said jaws and having its free end engaging the other of said jaws to releasably hold said jaws in an open position.

In testimony whereof I affix my signature in presence of two witnesses.

BARNEY L. HUFF.
